DESIGN FOR A THERMOHYDROMETER OR THE LIKE

Leo Edelmann, Chicago, Ill.

Application December 29, 1944, Serial No. 117,155

Term of patent 14 years

(Cl. D52—7)

To all whom it may concern:

Be it known that I, Leo Edelmann, a citizen of the United States, residing at Chicago, in the county of Cook and State of Illinois, have invented a new, original, and ornamental Design for a Thermohydrometer or the like, of which the following is a specification, reference being had to the accompanying drawing, forming a part thereof, and in which:

Figure 1 is a view in perspective looking downwardly toward one side of a thermohydrometer showing my new design.

Fig. 2 is a top plan view.

Fig. 3 is a bottom plan view.

I claim:

The ornamental design for a thermohydrometer or the like, substantially as shown.

LEO EDELMANN.
